UNITED STATES PATENT OFFICE.

TOMLINSON FORT JOHNSON, JR., OF ATLANTA, GEORGIA.

JACK FOR DEAD-END INSULATORS.

Application filed August 12, 1922. Serial No. 581,452.

To all whom it may concern:

Be it known that I, TOMLINSON F. JOHNSON, Jr., a citizen of the United States, residing at Atlanta, in the county of Fulton and State of Georgia, have invented new and useful Improvements in Jacks for Dead-End Insulators, of which the following is a specification.

This invention relates to improvements in jack screws, and particularly to jacks designed to be used in the changing of dead end insulators for high voltage transmission lines.

It is well known that dead end insulators depreciate faster and must be replaced oftener than other types of insulators. When dead end insulators must be renewed, the ordinary method is to shut down the transmission line, and by means of rope tackle 10 take the strain of the line off the defective insulator so that it can be removed. Another method, usable on live lines, employs a short insulating tension rod in combination with rope tackle, the rod being placed between the tackle and the come-along. The rope tackle takes up a great deal of space, therefore limiting the length of the insulating rod to 2 feet or less. Since it is possible to reach only a limited distance out on the transmission line when placing the come-along, the combination of rope tackle and rod becomes prohibitively dangerous when the voltage of the line is high. Thus with known apparatus following known methods 20 it is absolutely impossible to change dead end insulators safely on live transmission lines carrying more than 66,000 volts.

Another disadvantage of rope tackle is that when the men are pulling on the rope to take up a heavy load (some conductors have a tension of 10,000 lbs.) the rhythmic jerks start oscillations of the line, which are dangerous because the line is liable to swing into contact with another live line of the system and burn out the circuit. Again, the fall rope of the tackle may slip through the hands of the workmen and always must be tied at the finish of the pull. Furthermore, the rope is continually stretching and in the course of time becomes rotten and must be renewed.

In accordance with the present invention, a jack is provided to take the tension off insulators, by means of which a single workman can exert a pull of 10,000 lbs., whereas

five or six men would be needed to pull that much with tackle. The jack does the pulling gradually and smoothly without jerking and hence oscillations of the line are not set up; and there is never any danger of slipping or breaking. By employing one of my jacks, the maintenance crew can change dead end insulators on live lines carrying 300,000 volts or more, since an insulating stick five feet in length or longer may be easily handled.

The jack cannot wear out; it is lighter and more easily carried than tackle; it is more quickly mounted on the tower or pole and more readily put in operation.

The invention has other aims and advantages which will appear from the following description of a preferred embodiment thereof.

In the accompanying drawings forming a part of this specification, there is shown, by way of illustration, a jack constructed in accordance with the invention, wherein:

Figure 1 is an elevation showing the jack in operation on a transmission tower;

Figure 2 is a sectional elevation of the jack;

Figure 3 is an elevation of the same looking from the right side of Figure 2;

Figure 4 is a diametric sectional view of the housing or casing of the jack.

Figure 5 is an end elevation of the same;

Figure 6 is an end elevation of the nut of the jack;

Figure 7 is a diametric section of the same;

Figure 8 is a plan of the washer which retains the nut in place.

Referring more specifically to the illustrative embodiment of the invention shown in the drawing, there appears, as best shown in Figures 2 and 3, a clamp 10 of any well known form mounting the jack proper and adapted to hold said jack on a cross arm of a pole, on a tower (as seen in Fig. 1) or other support. One arm of the clamp 10 carries or is formed into a pair of spaced flanges, conveniently provided by a section of a channel bar or else two angle bars 11 bolted or riveted to said arm and extending at right angles, as shown in Figure 2. Preferably the two flanges are bored so that a pin 12 may be inserted through the bores to turn axially therein and form a swivel connection between the jack and the supporting clamp. The head 13 of the pin is

bored to receive a bolt or the like 14, which also is passed through the ends of a U-shaped strap 15 embracing the hollow casing or housing 16 of the jack. This casing has 5 ears 17 with perforations (Fig. 4) for the bolt 14. The arrangement is such that the casing may swing about bolt 14 as an axis, and also about the axis of pin 12; or in other words, the jack is mounted to move in two 10 planes at right angles. This enables the jack to be used in replacing two dead end insulators without changing the position of the clamp. (See Fig. 1.)

Obviously there are many constructions 15 other than the one illustrated by means of which the jack may be secured upon a cross arm or the like to swing in two planes, and the invention is not limited to the particular jack mounting shown.

20 The housing 16 is formed so that for about one-half of its length a cup-like recess is provided within which a thrust ball bearing 18 is held, as shown in Fig. 2. A nut member 19 whose construction is clearly 25 shown in Figs. 6 and 7, is held within the casing or housing 16 by a disk or washer 20, shown separately in Fig. 8. The washer 20 is held against rotation by radially extending 30 screws 21, while the nut 19 is freely rotatable between the washer and the ball bearing. One end of the nut has a neck 22 which protrudes out of the casing and a radial lug 23 is formed on said neck, as shown.

The nut is internally screw threaded to 35 engage with a threaded steel rod 24 having a clevis 25 or the like on one end. Rod 24 extends through the casing 16 as shown. The clevis provides convenient means by 40 which the jack screw may be connected with the transmission line. In order to turn the nut 19 and thus move rod 24 longitudinally to exert a pull, a wheel or sheave 26 is mounted on the neck 22. Preferably the hub of the sheave has a slot 27 of a size to 45 pass the lug 23 on the neck 22, and a rib 28 adapted to engage against the lug 23 after the sheave is in position and has been turned. The construction permits easy and 50 rapid removal of the sheave and the substitution of a larger or smaller sheave if desired.

55 Referring now to Fig. 1, there the jack is shown in the act of taking the load of line 29 off the dead end insulators 30 supported upon a tower 31. The jack is clamped upon the cross arm 32 of the tower. In order to make elevation of the jack to the cross arm easier, a clevis 33 is pivoted to the casing 16 of the jack. The clevis 25 is connected with 60 the hook of the insulating stick 34, supported from above during coupling and uncoupling by a rope 35. The other end of the stick or rod 34 also carries a hook engaged with a come-along 36 gripping the transmission line 29.

In order to turn the sheave 26 and thus transfer the tension of the line to the jack, a rope 37 passes over the sheave and is received within the peripheral groove thereof as shown. One end of this rope may be secured to the sheave, or the rope may be endless and secured at one point to the sheave, so that pulling on the rope in the direction indicated by the arrow will move rod 24 to the right, and moving the sheave in the opposite direction will slacken the line. Obviously, whatever the angular position of the sheave, it may be turned easily by means of the rope.

It will now be plain that all the above- 80 mentioned disadvantages of using devices such as tackle for replacing dead-end insulators are eliminated by employing the described jack; but it will be clear that the construction of my jack may be varied and 85 yet accomplish the same results; and that its uses are manifold. My invention, then, is not to be considered as limited to or by the showing of the drawings.

Having described one embodiment of the 90 invention, what I claim and desire to secure by Letters Patent is;

1. In combination with a jack screw, a 95 clamp adapted to mount the jack screw on a transmission line support, and means connecting the clamp and the jack screw whereby the latter may turn in two different planes after the clamp is secured in position.

2. In combination with a jack screw, a 100 clamp adapted to mount the jack on a cross arm of a transmission line support, means connecting the clamp and jack whereby the latter may turn in two planes after the clamp is fixed, and means for operating the jack from the base of the tower.

105 3. In combination with a jack screw and a mounting therefor adapted to hold the jack upon a transmission line support adjacent the dead end of such line, means on one end of the screw enabling it to be connected with a transmission line, a wheel adapted to operate the jack to take the load off the transmission line, and flexible means engaging the wheel to enable an operator to turn the wheel in either direction from a 110 distance.

115 4. In combination with the stick having a hook at one end, means connecting the other end of the stick with the transmission line, a rod having a clevis at one end engaged with said hook, said rod having threads, a casing carrying a nut engaged with said rod, and means for turning said nut on said rod.

120 5. In a jack, in combination, a hollow casing, a screw-threaded rod received within the casing but out of engagement therewith, a nut revolubly mounted in the casing with its threads engaging those of the rod, and a 125 wheel detachably mounted on the nut so 130

that a partial rotation of the wheel is necessary after mounting before the nut rotates with the wheel.

6. In combination, a clamp, a jack screw mounted on the clamp to rock in two planes at right angles, said jack including a rotatable nut and a rod moved endwise by rotation of the nut, a wheel for rotating the nut, and a flexible element for turning the wheel 10 whatever its position relative to the clamp.

7. In a jack, in combination, a hollow casing, a thrust bearing in the casing, a nut between the bearing and casing and rotatably carried, a screw-threaded rod passing 15 through the casing and engaging the nut with its threads, means on one end of the rod whereby it may be engaged with a part to be pulled, means for rotating the nut, and means for supporting the casing so that it 20 may rock in a horizontal plane as well as in a vertical plane.

8. In a jack having a screw threaded rod moved longitudinally by rotation of a nut member with which its threads are engaged, 25 a neck formed on said nut and having a radial lug, a sheave mountable upon the neck and having a slot to pass said lug, and a rib

on the hub of the sheave engageable with the lug when the sheave is turned whereby rotation of the sheave causes similar movement of the nut. 30

9. In combination, a jack screw adapted to be used in changing dead end insulators, and a mounting therefor adapted to hold the jack upon an insulator support, said 35 mounting including a clamp, a pin swiveled in the clamp, and means pivotally connecting the jack screw with one end of the pin.

10. A jack screw having supporting means adapted to mount the jack on the cross arm 40 of a transmission line support, said supporting means permitting swinging of the jack as a whole in both horizontal and vertical planes, said jack including a rotatable member and a longitudinally movable member, 45 means on the latter member whereby the transmission line may be supported from said jack, and means engageable with the former member for operating the jack.

In testimony, that I claim the foregoing 50 as my own, I have hereto affixed my signature.

TOMLINSON FORT JOHNSON, JR.
